METAL FABRIC.

1,309,241.

Specification of Letters Patent.

Patented July 8, 1919.

Application filed April 26, 1912. Serial No. 693,329.

To all whom it may concern:

Be it known that I, NORRIS ELMORE CLARK, a citizen of the United States, and resident of Plainville, in the county of Hartford and 5 State of Connecticut, have invented certain new and useful Improvements in Metal Fabrics, of which the following is a specification.

My invention relates particularly to what 10 is commonly known as metal lath and concrete reinforcing material.

Metal lath usually consists of expanded metal, perforated metal or woven or welded wire fabric. Sometimes the reticulated portion 15 is furnished in sheets or coils and attached to studding on the job. In other cases the fabric is solid and is provided with reinforcing members which serve as studding or as furring strips. My invention relates to 20 this latter type. The object is to provide a fabric which can be made economically and which will have great holding power so as to provide a maximum strength for a minimum amount of metal.

The invention in its preferred form 25 consists of expanded metal mesh-work together with reinforced beam members formed of strips of metal bent into channel-like form and projecting from the plane of the expanded portion. The beam members may be reinforced in either or both of two ways so as 30 to provide a maximum strength in the beams at the outer edges of the beams which are most remote from the plane of the reticulated section. The reinforcement of these beams may be effected either by providing a supplementary rod inside or outside the apex 35 of the beam member or by indenting the sides of the beams near their apices so as to stiffen the beams and provide shoulders and recesses into which the cement or concrete 40 can become interlocked with the sides of the beams so as to develop the compressive strength of the cement when in use. A combination 45 of these two methods of reinforcement may be effected by placing a rod inside the beam at its apex and then bending the sides of the beam inward so as to cause it to inclose the rod snugly. The expanded portion 50 of the fabric may be formed by slitting the metal between the beams in stag-

gered arrangement, the lines or slits being arranged diagonally relative to the direction of the beams and diverging from the center of the metal between the apices of the 55 adjacent beams. The slotted portions are then expanded in a suitable manner so that the expanded fabric consists of zig-zag bent strands united at a point midway between the beams and extending diagonally from 60 the center in opposite inclinations.

The preferred form and some modifications are illustrated in the accompanying single sheet of drawings.

Figure 1, is a transverse sectional view 65 of a fabric embodying the improvements of my invention.

Fig. 2, is a view of the under side of the 70 left hand portion of the same on an enlarged scale.

Fig. 3, is a side view of one of the beam members showing perforated sides.

Fig. 4, is a fragmentary transverse sectional view showing the method of connecting the ends of the beams of two sheets by 75 interlocking the beams.

Fig. 5, is a detail transverse sectional view showing the method of connecting the adjacent side edges of two sheets.

Fig. 6, is a perspective view of a modification 80 showing a separately formed beam member secured to an expanded metal fabric.

Fig. 7, is a detail perspective view of a fragment of the beam of my invention having a triangular sectioned rod secured inside 85 the apex of a beam.

Fig. 8, is a cross sectional view of the same.

Fig. 9, is a detail perspective view of a fragment of another form of a beam of 90 another form of my invention in which the beam is reinforced by a strip secured on the outside of the apex of the beam.

In the form shown in Figs. 1-5 inclusive the reference numerals 1, 2 and 3 indicate 95 what I have termed the beam members which provide the necessary rigidity so as to enable the fabric to be self-supporting. Any number of these beam members may be provided in the fabric but preferably the 100 fabric will be provided with at least one beam on each edge. In the form shown the beam 3

is shaped so that it can be snapped over a beam 1 of the adjoining sheet as illustrated in Fig. 5. The ends of the beams of longitudinally adjacent sheets may be overlapped 5 as shown in Fig. 4 by spreading apart the sides of the beams at one end of the fabric. The beams are connected by reticulated sections for instance, the expanded metal such as the sections 4 and 5.

10 Each beam member is formed of a longitudinal strip of metal folded into a cross section such as shown in Fig. 1. The lower edges of the sides of the beam 6 and 7 are spaced apart so as to leave a channel 8 between them. Just beyond the spaced apart portion the sides are closed in together to form longitudinal lateral channels 9 and 10. Preferably the outer edge is formed so as to have rather abrupt shoulders 11 and 12 to 15 afford a better grip in the cement. This bending in of the sides near the outer edge stiffens the metal and the lateral channels 9 and 10 and the shoulders 11 and 12 cause the cement to coöperate more perfectly with the metal so as to develop the maximum amount of tensile strength of the metal in conjunction with the compressive resistance of the cement.

Additional reinforcement such as the rod 30 13 in the apex of the beam may be provided if desired, the additional metal of this rod being located at a point removed from the plane of the reticulated sections makes the fabric particularly rigid against bending.

35 In the form shown in Figs. 1 and 2 the reticulated section is formed by slitting the metal along lines in staggered arrangement and then expanding it so as to form zig-zag strands 14 and 15 extending upward to the 40 left and to the right respectively as viewed in Fig. 2 from the central connection 16 diagonal relative to the beams. The connection 16 may be bent upward slightly as shown. The openings are preferably small 45 and the strands preferably arranged edge-wise so as to afford a good holding capacity for the cement. The sides of the beams may be provided with openings such as 17 for the cement to pass through into channels 50 between the sides and thus more efficiently prevent the formation of lines of cleavage.

In the form shown in Fig. 6 the beam 20 has a cross section similar to the beams of Fig. 1 and extends in longitudinal direction 55 while the strands of the expanded fabric 21 extend transversely relative to the beam members. The beam member is provided with lateral flanges 22 and 23 which may be secured to the expanded fabric for instance, 60 by tangs 24 and 25 bent around some of the strands of the expanded portion.

In the form shown in Figs. 7 and 8 the beam member 30 is formed by corrugating or folding the strip of metal along its center. Additional reinforcement consists of 65

a rod 31 having a cross section of general triangular shape. This rod may be secured in place, for instance by extending the portion 32 into the rod or by bending over tongues 33 so as to retain the rod securely 70 and prevent it from creeping longitudinally and from falling out. In cutting and bending the tongues 33, openings such as 34 are left in the sides below the rod for the cement to pass through and inter-connect the 75 same on the opposite sides.

In the form shown in Fig. 9, the beam member 40 is indented or grooved along the sides of the upper edge so as to provide 80 channels such as 41 and additional reinforcing metal is provided in the form of a strip 42 rolled over the outer edge into the channels 41.

By the use of a fabric having the reinforced beam members as herein set forth it 85 is possible to obtain a maximum stiffness of fabric with a minimum amount of metal since the additional metal or reinforcement formed by indenting the sides is located at some distance from the surface of the reticulated portion of the fabric. In this manner it is possible to do away with some of the rod members which would otherwise be necessary to supply the requisite stiffness. 90 Similarly the requisite stiffness may be provided without using as heavy a gage of metal as would be otherwise necessary. By using the additional metal as shown in Figs. 1, 7 and 9 it is possible for the manufacturer to supply two grades of fabric made on the 95 same machine, by simply omitting the rods in one case and putting in the additional rods when greater stiffness is desired. By allowing the ends of the rods to extend as shown in Fig. 7 beyond the sheet metal portion of the beams it is possible to connect up two sheets of the fabric end to end more readily. In the form shown in Fig. 6 the expanded metal portion is very stiff in one direction and the beams give additional stiffness in the opposite direction. 100 105 110

In my application #296,087, filed May 10, 1919, I am claiming more specifically the forms of construction having the features illustrated in Figs. 6 and 9 herein. 115

What I claim is:—

1. An expanded metal fabric comprising beam members bent into channel-like form and an expanded section connecting said beam members and consisting of two sets 120 of zigzag strands arranged edge-wise to the plane of the fabric and extending diagonally in opposite inclinations relative to the length of the beams and connected midway between the beams by discontinuous connecting portions forming tangs bent from the plane of the fabric. 125

2. A metallic reinforcing fabric consisting of the combination of a reticulated section having small meshwork and longitudi- 130

- nal beams strengthening and reinforcing the small meshwork, said beams bent into channel-like form with their sides spaced apart at the connection with the reticulated section 5 and bent inward at both sides near their outer edges to form longitudinal lateral channels on the opposite sides of the beams, the outer edges of the beam members extending substantially parallel to the plane of 10 the fabric at the opposite sides so as to provide abrupt longitudinally extending shoulders to interlock with the cement covering the fabric.
3. A metal fabric comprising the combination of a sheet metal portion consisting of a reticulated section having a plurality of rows of relatively small openings and longitudinal, relatively deep, channel-like beam members each closed at one edge, and 15 with inclined sides spaced apart at its base and integral with the reticulated section and projecting from the plane thereof together with an additional separately formed longitudinal reinforcing rod rigidly secured to 20 the beam member at the apex thereof.
4. An expanded reinforcing fabric comprising, expanded meshwork and marginal channel-like beam members, each being closed at one edge and open at the other 25 edge, an additional reinforcing rod secured in the channel of one of said beams adjacent the apex thereof, the other marginal beam member being left open to the apex to receive the marginal beam member of another 30 sheet of such fabric.
5. A building fabric comprising an expanded meshwork section forming a support for concrete on the upper side and an anchorage surface for plaster on the under 35 side and relatively narrow and unexpanded channel-like high ribs projecting from the upper side serving to reinforce and support the expanded meshwork section and its load 40 of wet concrete and to support substantial direct loads, said ribs being continuous along 45 their upper and lower edges and spaced apart from each other a distance materially greater than the height of the ribs and having lateral shoulders near their upper edges 50 serving to anchor the ribs in the hard concrete and to prevent the formation of lines of cleavage in the concrete along the upper edges of the ribs.
6. A building fabric comprising an expanded meshwork section forming a support for concrete on the upper side and an anchorage surface for plaster on the under side and relatively narrow and unexpanded high 55 ribs projecting from the upper side serving 60 to reinforce and support the expanded meshwork section and its load of wet concrete and to support substantial direct loads, said ribs being continuous along their upper and lower edges and spaced apart from each 65 other a distance materially greater than the height of the ribs and having lateral shoulders near their upper edges serving to anchor the ribs in the hard concrete and to prevent the formation of lines of cleavage in the concrete along the upper edges of the ribs.
7. An expanded metal fabric comprising beam members bent into channel-like form and an expanded section connecting said beam members and consisting of two sets of zig-zag strands arranged edgewise of the plane of the fabric and extending diagonally in opposite inclination relative to the length of the beam members and connected midway 70 between the beam members by tangs, said strands having between them relatively small meshes and the meshes midway between the beam members being of greater 75 from below and thereby prevent the spreading of the sides of the ribs.
8. A metal reinforcing fabric comprising an expanded metal meshwork section forming a support for concrete on the upper side and an anchorage surface for plaster on the under side and relatively narrow and unexpanded metal ribs projecting from the upper side and serving to reinforce and support the meshwork section and its load of wet concrete and to support substantial direct loads, said ribs being continuous along 80 their upper and lower edges and spaced apart from each other a distance materially greater than the height of the ribs and each having continuous laterally projecting portions along their upper edges with abrupt 85 shoulders serving to anchor the ribs in the hardened concrete and to prevent formation of the sides of the ribs.
9. A reinforcing fabric for concrete work comprising, expanded metal meshwork and relatively high and narrow unexpanded ribs projecting therefrom and spaced apart at distances greater than the height of the ribs, each rib being continuous along its upper and lower edge and having a continuous 90 laterally projecting portion with an abrupt shoulder extending along its upper edge serving to prevent the formation of lines of cleavage in the concrete, and the two walls of each rib being in contact below the shoulder and having perforations between the shoulder and the meshwork.
10. A metal reinforcing fabric comprising an expanded metal meshwork section forming a support for concrete on the upper side and an anchorage surface for plaster on the under side and relatively narrow and high unexpanded metal ribs projecting from the upper side and serving to reinforce and support the meshwork section and its load of 95

wet concrete and to support substantial direct loads, said ribs being continuous along their upper and lower edges and spaced apart from each other a distance materially 5 greater than the height of the ribs and each having a lateral channel and a continuous laterally extending abrupt shoulder along its

upper edge and perforations between the shoulder and the meshwork.
